UNITED STATES PATENT OFFICE.

OLIVER G. SIMMONS, OF WASHINGTON, DISTRICT OF COLUMBIA.

COMBUSTION-ENGINE.

No. 903,902.

Specification of Letters Patent. Patented Nov. 17, 1908.

Application filed December 21, 1907. Serial No. 407,473.

To all whom it may concern:

Be it known that I, OLIVER G. SIMMONS, a citizen of the United States, residing at Washington, in the District of Columbia, 5 have invented certain new and useful Improvements in Combustion-Engines, of which the following is a specification.

This invention relates to internal combustion or hydrocarbon engines designed for 10 either high or low speed, for general adaptability, either stationary or otherwise, and for either the single, compound, or multiple type.

One of the objects aimed at in the present 15 invention is to provide an engine of the type indicated which shall be possessed of a high degree of power and efficiency proportionate to the cost of construction and maintenance, and which shall be, therefore, easy of manipulation and certain of control throughout 20 all of its capabilities of operation.

Another and more specific object is to provide a novel and improved mechanism for supplying fuel from any suitable or well 25 known supply reservoir and delivering the same by regulated charges to a peculiar form of vaporizer in the ignition or combustion chamber.

Another object is to so design the construction that pure hot air shall be supplied 30 to the engine cylinder where it will not only support the operation of combustion but will also serve to purge the said cylinder of foul gases at each inflow of said air into the engine cylinder, the mixture of the vaporized fuel and air taking place only within 35 the cylinder and ignition chamber communicating therewith.

A further object of the invention is to 40 provide adjustable automatic means of peculiar form for governing the amount of fuel discharged at each impulse of the piston in one direction and also to vary the time of such discharge of fuel with respect 45 to the lead of the piston in accordance with the various requirements, as for instance in reversing the engine.

The foregoing and other objects of the invention which will presently appear are 50 attained by the mechanism hereinafter fully described and illustrated in the accompanying drawings, in which

Figure 1 is a vertical sectional view through the main parts of my engine, certain portions thereof being shown in elevation; Fig. 2 is a vertical section on the line

2-2 of Fig. 4 and showing the controlling mechanism partly in elevation and partly broken away; Fig. 3 is a view similar to Fig. 2 taken on the line 3-3 of Fig. 4; Fig. 4 is 60 a vertical sectional view of the means for feeding the fuel; Fig. 5 is a detail view of the pump operating cam; Fig. 6 is a like view of the adjustable abutment for varying the throw of the pump plunger, and Fig. 7 65 is a fragmentary view indicating the form of the connecting member for the automatic governor.

Corresponding and like parts are referred to throughout the following detail description and indicated on the several views of the drawings by the same reference characters.

While this engine is designed primarily for operation by a combustion of crude oil 75 as a fuel, it is adapted also for the use of gasolene, alcohol, or any other well known kind of hydrocarbon. It is to be noted also that while I have illustrated a vertical type of engine, it is to be understood that the 80 improvements herein set forth are applicable also to engines of the horizontal type, and while I have illustrated what I consider to be the best form of my improvements, it is to be understood that some slight variations 85 thereof may be resorted to by those skilled in the art without departing from the spirit of the invention or sacrificing any of its advantages.

Referring now to the accompanying drawings, the engine comprises a cylinder A, piston B, crank casing C, crank shaft D, and connecting rod E. The foregoing elements are or may be of any suitable design, and *per se* constitute no part of my present invention. Mounted upon the compression end of the cylinder A and communicating therewith is a combustion or ignition-chamber 10 into which the fuel is designed to be fed and therein vaporized. The ignition 100 chamber is fitted with a spark plug 11 of any suitable construction, and except as hereinafter set forth is adapted for its well known purpose of igniting the mixed vapor and air with the ignition chamber and cylinder. The fuel is fed to the ignition chamber or vaporizer therein by any suitable means, preferably by means of the peculiar form of pump hereinafter specifically described, and is forced through a peculiar 110 form of feed pipe or nozzle 12 having a small bore 12' directed into the vaporizer 13.

In the initial operation of the engine gasoline or some similar hydrocarbon fuel is supplied to the feed means through a charging cup or funnel 14 and into a reservoir 15 supported by a rigid portion 16 of the feed pipe. Suitable valves are supplied to the feed pipe for the purpose of draining the feed pipe and filling the reservoir as herein indicated. Upon operation of the fuel feeding or charging mechanism the fuel is forced into the ignition chamber in a fine stream at frequent intervals and therein is ignited by a spark from the spark plug 11 in a well known manner. After a brief operation of the engine in this manner the walls of the ignition chamber 10 and the vaporizer 13 become so hot that the fuel introduced thereto will become immediately vaporized by virtue of the vaporizer 13, without engaging the structure of the vaporizer or the walls of the ignition chamber while in a liquid state and the same will immediately ignite by spontaneous combustion, the sparking apparatus at such time being thrown out of operation by any suitable form of switch, or the like. The vaporizer 13 is herein indicated as being a hollow tubular member extending within the ignition chamber practically to the center thereof, and being provided with numerous perforations whereby the operation of vaporization of the introduced fuel and the subsequent mixture thereof with the air in the cylinder and combustion of the mixture is facilitated. The ignition chamber is unjacketed for the reason that it is desired that it be kept hot, but is guarded by a shield or guard 17 as indicated.

The cylinder A is jacketed by a well known form of water jacket 18 to which a cooling medium is supplied through a pipe 19 and from which the same may circulate through the pipe 20. In order to keep the temperature of the fuel supplied to the engine at a sufficiently low temperature so as to prevent any possibility of vaporizing thereof before it is admitted to the vaporizer 13, I provide a jacket 21 surrounding the nozzle 12 and through which the cooling medium may pass, the same being brought into communication with the main cylinder jacket through the flexible pipes 22 and 23.

The cylinder A is provided with an air inlet port 24 and an exhaust port 25. The inlet port is located substantially at the compression end of the cylinder, and preferably the exhaust port is located at the opposite end thereof. The exhaust port 25 communicates with the tubular outlet 26, the walls of which become highly heated during the operation of the engine by reason of contact therewith of the highly heated products of combustion. The air jacket or passage 27 embraces said outlet and passage 26 and a pipe 28 leads therefrom into the crank casing C. On the operation of the piston B, fresh,

pure, or atmospheric air is drawn directly into the crank casing at a point remote from the piston through the passages 27 and 28, such air being drawn into the passage 27 in small jets through a series of small holes 29 and coming into contact with the walls of the passage 26 becomes highly heated. A check valve 30 prevents backward movement of such heated air from the crank casing and communicating with the intake port 24 of the cylinder is a passage 31 through which fresh, pure hot air is supplied from the crank casing directly to the clearance space of the engine cylinder, a check valve 32 guarding its passage in a manner similar to that already described. Each of the check valves 30 and 32 is provided with adjusting means as shown. By utilizing fresh hot air for application to the engine cylinder the operative parts are not subjected to any chilling effect which would be incidental to the use of ordinary atmospheric air, it being essential in the usual operation that the walls of the ignition chamber be maintained at a high temperature. It is to be observed furthermore in this connection that all vaporizing of the fuel takes place within the walls of the ignition chamber and that the air supplied to support the combustion thereof and any incidental mixture of vapor and air takes place entirely within the ignition chamber and engine cylinder communicating therewith.

The engine herein illustrated being of the two cycle type, fuel is admitted to the vaporizer and ignition chamber at each rotation of the crank and also pure hot air is admitted under compression into the cylinder once during each rotation. It will be seen therefore that at each positive stroke of the piston the admitted fresh air will purge the cylinder of foul gases, a sufficient quantity of such pure fresh air being retained in the cylinder for the purpose of the next combustion. As a suitable means for introducing fuel to the ignition chamber and in co-operation with the feed pipe or nozzle above described, I employ a pump 33 having a plunger 34 which is operated in one direction positively by a member secured to the crank shaft, such member being indicated as a cam 35, and operated in the opposite direction by a spring 36. It will thus be seen that at each rotation of the crank shaft the pump plunger will be given a positive impulse to feed fuel through the feed pipe and into the vaporizer. In order to vary the time at which such feeding of fuel takes place with respect to the position of the piston the member 35 and the pump 33 are relatively adjustable. As indicated herein the cam 35 bears a fixed relation to the crank shaft while the pump is adjustable therearound.

The pump mechanism is mounted upon a casing 37 to which is secured a suitable hand

lever 38 having adjustable coöperation with a segment 39 secured to the crank casing C. By movement of the pump through the means indicated circumferentially about the 5 crank shaft, the time at which the cam 35 would engage the roller 40 to operate the plunger may be varied in accordance with the desire of the operator, according to the direction in which it is desired to operate the 10 engine or in accordance with the character of fuel used, or the like. For the purpose of such adjustment pipe 41 leading thereto from any suitable reservoir for fuel and pipe 42 leading therefrom toward the reservoir 15 will be made of flexible material. A 15 branch pipe 43 is employed for connection with the main feed pipe in order that the contents of the same and reservoir 15 may be drained back into the main fuel reservoir 20 initial to the introduction of gasoline, or the like, into the feed pipe in priming the engine as above indicated. During the operation 25 of the priming of the engine it is desirable that the spark shall take place at a certain definite time relative to the operation of the plunger. To this end I provide a spring contact point 44 so mounted upon the inner wall of the casing 37 as to be carried thereby during its adjustment and lying in 30 the path of a projection 45 on the said plunger. On each stroke of the plunger the projection 45 will make an electrical contact with contact blade 44 closing the circuit.

In order to vary the length of stroke of 35 the pump plunger and thereby vary the amount of fuel fed to the ignition chamber with the consequent variation in the speed of the engine, I provide a suitable means for limiting the movement of the plunger. 40 through its operation by the spring 36. To this end the plunger or a shoulder 46 thereon is adapted to engage an adjustable abutment 47, the position of the abutment determining the length of the stroke of the plunger. 45 Said abutment may be supported and operated by any convenient means. I have indicated herein that the same is carried upon an annulus 48 embracing the crank shaft D and adjacent to the cam 35. The 50 annulus 48 but for its adjustment for the operation herein indicated is stationary, the crank shaft and cam 35 rotating with relation thereto. The abutment 47 is indicated as being cam shaped and upon movement of 55 its supporting means about the axis of the crank shaft the cam face will cause the desired variation in throw of the plunger. Adjustment of the abutment 47 may be effected by any suitable means, that herein indicated 60 being an automatic means through its connection with a centrifugal governor 49. The governor mechanism is mounted upon the movable casing 37 and hence always bears a definite relation to the pump mechanism. A 65 governor shaft 50 journaled in said casing

37 is driven through worm gearing directly from the crank shaft. The proper sensitivity of the governor may be determined by means of a spring controlled rod 51 having an adjustable turnbuckle connection 52 to 70 an arm 53 secured to the annulus 48. Upon excessive speed of the engine the governor will cause the arm 53 to be elevated, moving the abutment 47 in the direction indicated by the arrow of Fig. 2, reducing the feed of 75 the pump.

The cam 35 and worm 54 are preferably keyed to the crank shaft for positive operation therewith and are held from displacement thereon by suitable locknuts 55. The 80 casing 37 may if desired be supplied with suitable lubricant. As indicated in Fig. 4 the crank shaft D may project sufficiently far beyond the casing 37 for the application of a crank in starting the engine. A fly 85 wheel 56 may if desired be applied at either end of the crank shaft D.

On the compression stroke of the piston, the pure hot air is compressed into the combustion chamber, and since the compression 90 pressure may be anything for which the engine is designed without liability to pre-ignition expansion could be carried to a high degree by adjustment of the pump stroke to suit the fuel being used. This will permit 95 the engine to be built with the smallest possible mechanical clearance, as at a, and will greatly enhance the efficiency and desirability of the engine, without the disadvantages usually incidental to the ordinary two and 100 four cycle hydrocarbon engines. It is to be noted, furthermore, that since the whole charge of vapor is not burning at any one time, there is nothing in the nature of a violent explosion. The vapor being formed 105 entirely within the ignition or combustion chamber, and being ignited by spontaneous combustion, will burn with any excess of air present.

Having thus described the invention what 110 is claimed as new is,

1. In a hydrocarbon engine, the combination of a cylinder, a piston therein, an ignition chamber at one end of the cylinder, said end having a clearance space, an exhaust port and tubular passage leading from the cylinder, a fresh air jacket embracing said tubular passage, the walls of said jacket being provided with numerous small holes 115 through which fresh air is introduced into the jacket and whereby the said air impinges in small jets against the heated walls of the exhaust passage, a crank casing connected to the end of the cylinder opposite the ignition chamber, a passage through 120 which the heated fresh air is conveyed from said jacket directly into the crank casing, at a point remote from the piston, a movable valve in said passage, a second passage leading 125 from the crank casing and conveying the 130

heated fresh air directly into said clearance space of the cylinder, and a movable valve in said second passage.

2. In a hydrocarbon engine, the combination of a cylinder, an ignition chamber communicating therewith, a piston in the cylinder, a shaft operated by the piston, a pump associated with said shaft to supply charges of fuel to the ignition chamber, a member mounted upon the shaft aforesaid to operate said pump, and means for adjusting the pump circumferentially around the shaft whereby the introduction of fuel into the ignition chamber and the combustion thereof may be varied with respect to the position of the piston.

3. The combination with the cylinder having a water jacket, piston, and crank casing, of an unjacketed ignition chamber communicating with the cylinder, a vaporizer associated with said ignition chamber and comprising a hollow perforated open-ended cylindrical member extending within the chamber, a water jacketed feed pipe exterior to the chamber and to which said cylindrical member has threaded connection, the water jacket of the feed pipe being in communication with the main cylinder water jacket, and means for feeding fuel to and through the vaporizer.

4. A hydrocarbon engine comprising, in combination, a cylinder, an ignition chamber communicating with the cylinder, and means for supplying liquid fuel to the ignition chamber, the same including a valved pipe, a charging cup mounted on the upper portion thereof, a reservoir to receive the charge from the cup, and means to force the liquid fuel from the reservoir and pipe into the ignition chamber.

5. In an engine of the type described, the combination with the cylinder, piston, ignition chamber, and crank shaft, of means for

feeding fuel to the ignition chamber, said means including a pump having a plunger, means secured to the crank shaft for operating the plunger in one direction, automatic means to operate the plunger in the opposite direction, and means for varying the effect of said automatic means so as to vary the quantity of fuel delivered by the pump, said last mentioned means including a member mounted loosely on the crank shaft and a cam on said member adapted to be engaged by the said plunger when operated by the said automatic means.

6. In combination with the cylinder, piston, ignition chamber, and crank shaft of a hydrocarbon engine, of a pump for feeding fuel to the ignition chamber, said pump comprising a plunger, a cam for positively operating the plunger in one direction, a spring to operate the plunger in the opposite direction, and means driven from the crank shaft for automatically varying the length of stroke of the pump plunger when operated upon by the spring, said means including an annulus mounted upon the crank shaft and a cam secured to the annulus.

7. In a hydrocarbon engine, the combination with the cylinder, piston, ignition chamber, and crank shaft, of a pump for feeding fuel to the ignition chamber and comprising a plunger, means for adjusting the pump mechanism circumferentially about the crank shaft, means on said shaft to operate said plunger radially relative thereto in any position of adjustment, and means to vary the length of the stroke of the plunger.

In testimony whereof I affix my signature in presence of two witnesses.

OLIVER G. SIMMONS.
